ABSTRACT OF THE DISCLOSURE

An r.p.m.-dependent regulator for varying the fuel quantities delivered by fuel injection pumps, including a control element formed as a piston that reciprocates in a bore with a frequency depending upon the r.p.m. of an internal combustion engine associated with said fuel injection pumps; an accumulator into which liquid is displaced by the control element during each pressure stroke, a spring-biased accumulator piston which, during each suction stroke of the control element, forces the liquid out from the accumulator; conduit means which are opened and closed by the control element in such a coordinated manner that during each suction stroke, provided the frequency of reciprocation of the control element exceeds a predetermined r.p.m., the liquid displaced from the accumulator is allowed to expand into a cylinder displacing to a varying extent a regulating piston connected to the fuel quantity control members of the fuel injection pump.

Background of the invention

The invention relates to a hydraulic regulator particularly for fuel injection pumps of internal combustion engines. The regulator has a piston-operated accumulator including a spring which urges the accumulator piston against an abutment into its position of rest and wherein the force of the spring varies with its excursion. The accumulator is adapted, first to be hydraulically connected with a liquid source under pressure, causing the accumulator spring to be compressed so that its force increases and secondly, to be hydraulically connected with a regulating device including a spring-biased regulating piston that is periodically exposed to the pressure prevailing in the accumulator.

It is known in the prior art to provide a fuel injection pump with a hydraulic regulator wherein the pump work chamber of the fuel injection pump has a discharge channel which is opened by the accumulator piston after the pump has executed a predetermined portion of its stroke. Fuel injection is thus terminated before the end of the delivery stroke. Such a regulator, which may be used only with fuel injection pumps having a single pump work chamber, is disclosed in U.S. patent to P. E. Bessière, No. 3,141,414.

Object and summary of the invention

A principal object of the invention is to provide an improved hydraulic regulator which is adapted to adjust the quantity control member of a multi-cylinder pump, such as the quantity control rod of a serially connected pump.

Briefly stated, the aforesaid hydraulic connections are made and broken by a control element in such a coordinated manner that the accumulator, after being cut off from the liquid source and before being connected to the regulator, is in communication with a

2

chamber of lower pressure for a duration which is a function of the r.p.m. to be regulated. The conduit connecting the accumulator with said chamber of lower pressure includes a throttle passage to dampen the motion of the accumulator piston.

According to a preferred embodiment of the invention, the control element, driven with a speed depending upon the r.p.m. to be regulated, is a piston which executes alternating pressure strokes and suction strokes. The bore in which the control element reciprocates defines a pump work chamber which, during said pressure strokes performs the function of the aforesaid liquid source and during said suction strokes is transformed into the aforesaid chamber of lower pressure.

Brief description of the drawings

FIGS 1-4 are axial sectional views of an embodiment of the invention is different operational positions.

Structural description of the embodiment

In a bore 1a of a housing H there is disposed a control element 1 which serves both as a pump piston and as a control shuttle. The control element reciprocates to and fro with a frequency proportion to the r.p.m. of an internal combustion engine to which fuel is delivered by an injection pump associated with the regulator according to the invention. While the pressure stroke or inward motion of the control element 1 is effected by means not shown, such as a cam, the return force for the suction stroke or return motion of element 1 is supplied by a spring 2. The outer cylindrical face of the control element 1 in the vicinity of the upper end thereof is provided with a circumferential annular groove 3 which is connected with a pump work chamber 5 through a conduit 4 extending within the control element 1. Chamber 5 forms the upper terminal section of bore 1a.

The pump work chamber 5 is supplied with liquid through a conduit 6 which is in continuous communication with a liquid supply tank, schematically indicated at 7. Communication is established between conduit 6 and chamber 5 through conduit 4 and groove 3 as the latter registers with conduit 6 when the control element 1 is in, or adjacent, its lower dead center.

In a bore 8a of housing H there is slidably disposed an accumulator piston 8 which delimits an accumulator chamber 9. In bore 8a there is also disposed a spring 22 which urges the accumulator piston 8 into a position of rest against an abutment 21 fixedly held at the lower end of bore 8a. In the position depicted in FIG. 1, the tension of, or the force exerted by, spring 22 is at a minimum value. The more the accumulator piston 8 is displaced from its position of rest by means to be described later, the more the spring 22 is compressed and thus the greater its bias will be. Simultaneously with the increase of the bias of spring 22, the hydraulic pressure in accumulator chamber 9 also increases as it will become apparent later.

The pump work chamber 5 communicates with the accumulator chamber 9 through a conduit 10 in which there is disposed a check valve 11 permitting a liquid flow only from the pump work chamber 5 to the accumulator chamber 9 while blocking any flow in the opposite direction. During each pressure stroke, the control element 1 displaces a determined quantity of liquid into the accumulator chamber 9 so that the accumulator piston 8 is displaced from its position of rest into a new position where it opens a transfer port 23 which is connected to the low-pressure liquid tank 7. This condition is shown in FIG. 2. The position of accumulator piston 8 represented by this figure thus places an upper limit for the maximum possible pretensioning of spring 22 and consequently for the maximum possible hydraulic pressure in the accumulator chamber 9.

From accumulator chamber 9 there extend two conduits 12 and 16, merging into bore 1a at different heights thereof. As the control element 1, subsequent to a pressure stroke, performs the initial or first part of its return or suction stroke, at least part of the liquid, displaced into accumulator chamber 9 during the preceding pressure stroke, will flow therefrom through conduit 12 and its throttle passage 13, the sectional area of which is adjustable by means of a throttle needle 13a.

Simultaneously with said liquid flow, the accumulator piston 8 moves in the direction of its position of rest toward abutment 21 and is damped in its motion by virtue of the throttle passage 13. The duration of liquid flow through conduit 12 is dependent upon the r.p.m. of the engine as it will become more apparent as the specification progresses.

During the second part of the suction stroke of control element 1, communication is established through conduit 16 between the accumulator chamber 9 and a cylinder 15 in which there is slidably disposed a regulating piston 18. This hydraulic interconnection of the accumulator chamber 9 with the cylinder 15 occurs during the suction stroke after the groove 3 shifts out of alignment with respect to conduit 12. The aforesaid connection between chamber 9 and cylinder 15 is interrupted before, during a subsequent pressure stroke of the control element 1, liquid is displaced from the pump work chamber 5 into the accumulator chamber 9. The regulating piston 18 is biased by means of a spring 19 which urges it into a position of rest against an abutment 20 fixedly held within the cylinder 15. The regulating piston 18 is connected to a quantity regulating element, such as a regulating rod, of the fuel injection pump.

During the pressure stroke of the control element 1, the conduit 12 is opened by registry with the annular groove 3 when the control element 1 approaches its upper dead center. As a result, the conduit 12 will be connected with the pump work chamber 5 through conduit 4, so that the liquid displaced by the control element 1 will be forced into the accumulator chamber 9 not only through conduit 10, but also partially through conduit 12. As soon as the control element 1 starts its suction stroke, the accumulator piston 8, driven by its spring 22, starts its return stroke during which it displaces liquid from the accumulator chamber 9 into the pump work chamber 5 through conduit 12, throttle passage 13, annular groove 3 and conduit 4. As set forth hereinabove, the throttle 13 causes a braking of the return motion of the accumulator piston 8. This return motion is interrupted at the moment when the conduit 12 is closed as the groove 3 shifts out of registry therewith.

For establishing and interrupting interconnection of the accumulator chamber 9 with the cylinder 15, there is disposed on the control element 1 a second annular groove 14 which is of such a dimension that the conduit 16 is in communication therewith at all times during the operation of control element 1. Further, between the cylinder 15 and the bore 1a there is provided a port 17 which is arranged in such a manner with respect to the annular circumferential groove 14 that it will register therewith only after the conduit 12 is closed by the upper section of the control element 1. The port 17 remains open in the time period in which the control element 1 reaches its low dead center and will be closed again before the control element 1 begins to displace liquid from the pump work chamber 5 into the accumulator chamber 9.

During the time period in which the accumulator chamber 9 is in communication with the cylinder 15, the pressure in them is equal. If, now, both pistons 8 and 18 are in their position of rest at their respective abutments 21 and 20, there is no liquid flow across the conduit 16. Such a flow may occur only if either the accumulator piston 8 or the regulating piston 18 is away from its respective abutment.

The diameter of pistons 8 and 18 and the strength of springs 22 and 19 are selected such that the hydraulic pressure which is necessary to lift the accumulator piston 8 from its abutment 21 is somewhat larger than the hydraulic pressure which is required to displace the regulating piston 18 from its abutment 20.

The spaces for receiving springs 19 and 22 are connected to the ambient atmosphere through openings 28 and 27, respectively.

The accumulator piston 8, shortly before it opens the transfer port 23, opens a discharge port 24 which also leads to the liquid tank 7. The cross-section of the discharge port 24 is adjustable by means now shown. The function of the discharge port 24 is to slow down the motion of the accumulator piston 8 during the terminal part of its upward movement and serves, during the first period of the return motion of the accumulator piston 8, as an additional drain conduit. By these means the degree of non-uniformity of the regulator device may be affected. A similar result may be reached by changing the elasticity of the spring 22.

Port 17, which connects the cylinder 15 with the bore 1a may be provided with a throttle passage 25 in order to delay the establishment of a balanced pressure condition between the accumulator chamber 9 and the cylinder 15.

From the bore 1a there extends an additional drain conduit 26 which, by means of the circumferential annular groove 3 of the control element 1, is opened shortly before the control element 1 reaches its upper dead center. In any other positions of the control element 1 the drain conduit 26 is closed. By opening the drain conduit 26, the return motion of the accumulator piston 8, in case of a significant drop in the r.p.m. of the engine, is accelerated and, consequently, the regulator piston 18 is also allowed to rapidly move into its position of rest.

The abutments 20 and 21 may be adjusted by means not shown.

Operation of the embodiment

FIG. 1 shows the control element 1 in its lower dead center while the pistons 8 and 18 are in their position of rest at their respective abutments 21 and 20. The pressure of the liquid, which now flows from the liquid supply tank 7 to the pump work chamber 5, is not sufficient to lift the accumulator piston 8 from its abutment 21.

FIG. 2 shows the control element 1 at the end of its pressure stroke, that is, in its upper dead center after the liquid from the pump work chamber 5 has been displaced into the accumulator chamber 9. The accumulator piston 8 has been displaced into a position in which it opens at least the discharge port 24 but normally also the transfer port 23.

During the first part of the suction stroke of control element 1, that is, as long as the control element 1 maintains the conduit 12 closed, the accumulator piston 8 moves in the direction of its abutment 21. As long as the r.p.m. of the cam (not shown) driving the control element 1 does not exceed a predetermined value, the accumulator piston 8 attains its position of rest against abutment 21 before an interconnection is established between the accumulator chamber 9 and the cylinder 15 by opening the port 17 by control element 1 towards the end of its suction stroke. Stated in different terms, the liquid displaced from the accumulator chamber 9 by the returning accumulator piston 8 cannot, under the aforesaid r.p.m. conditions expand into cylinder 15 and have effect on regulating piston 18 because the annular groove 14 of control element 1 registers with port 17 only after the accumulator piston 8 has come to a rest against abutment 21. The regulating piston 18 remains, therefore, in its position of rest against its abutment 20 at which position the fuel injection pump delivers a maximum amount of fuel. If, now, the r.p.m. of the driving means associated with the control element 1 increases beyond a predetermined value as a response 75 for a corresponding increase in the r.p.m. of the engine,

the accumulator piston 8, dependent upon the cross-section of the throttle passage 13 which brakes its motion, does not return into engagement with its abutment 21 due to the earlier closing of conduit 12 by means of the control element 1 (FIG. 3).

At the moment, when the control element 1, towards the end of its suction stroke, opens by means of the circumferential annular groove 14 the channel 17, the liquid displaced by the downwardly moving accumulator piston 8, may flow from the accumulator chamber 9 into the cylinder 15. As a result, the regulating piston 18, as depicted in FIG. 4, is displaced towards the left. Due to this displacement, the fuel quantity supplied by the fuel injection pump is decreased by, e.g. linkage means, not shown, connected to piston 18 and a quantity control member of the fuel injection pump.

The more the r.p.m. of the driving means for control element 1 increases above the aforesaid predetermined value, the higher is the position of the accumulator piston 8 at the moment the conduit 12 is closed by the control element 1 and the more will the regulating piston 18 be displaced leftward during the end portion of each suction stroke of control element 1 and thus the more will the fuel quantities to be injected decrease. The uppermost position that the accumulator piston 8 may assume is determined by the location of the transfer port 23. In this position the spring 22 is compressed to a maximum extent, that is, the pressure in the accumulator chamber 9 has reached its highest value. This highest pressure is just sufficient to displace the regulating piston 18 into a position in which the fuel injection pump delivers a minimum amount of fuel.

As soon as the return motion of the accumulator piston 8 is stabilized, that is, its return strokes are of constant lengths and the regulating piston 18 has assumed a corresponding position, there is an equal pressure in the accumulator chamber 9 and in the cylinder 15. Consequently, when now the port 17 is opened at the end of each suction stroke of control element 1, no liquid flows from the accumulator chamber 9 into the cylinder 15.

If now, the r.p.m. of the driving means for the control element 1 again drops, then the location which the accumulator piston 8 reaches at the moment when the conduit 12 closes, shifts in the direction of the abutment 21. As a result, the conforming pressure in the accumulator chamber 9 also decreases so that the regulating piston 18 is, during the open position of port 17, displaced by spring 19 in the direction of its abutment 20 which results in an increase in the fuel quantity delivered by the fuel injection pump.

If the driving speed for the control element 1 drops rapidly, the drain conduit 26 causes an accelerated discharged of the accumulator chamber 9 and, consequently, the regulating piston 18 will move rapidly into its position of rest with the end result of an accelerated increase in the fuel quantity delivered by the fuel injection pump.

By an appropriate choice of the ratio of diameters of the accumulator piston 8 and of the regulating piston 18, the number of strokes may be determined which is necessary to move the regulating piston 18 from one position of equilibrium into another.

By changing the cross-section of the throttle passage 13, the aforesaid predetermined r.p.m. beyond which the novel regulator becomes effective, may be changed. Thus, the invention provides a regulator which may be set to maintain a desired r.p.m. anywhere between an idling speed and a maximum revolution per minute.

Conduit 12 may lead directly into a chamber of lower pressure such as the liquid supply tank 7. Here too, however, a control element should keep the conduit 12 open during the first part of the suction stroke and should shut off the same during the second part thereof.

Although only one embodiment of the invention has been depicted and described, it will be apparent that this embodiment is illustrative in nature and that a number of 75

modifications in the apparatus and variations in its end use may be effected without departing from the spirit or scope of the invention.

What is claimed is:

- 5 1. A hydraulic regulator adapted to be associated with fuel injection pumps for varying the quantities of fuel delivered by said fuel injection pumps to internal combustion engines, said regulator operating as a function of the r.p.m. of said engine and comprising,
  - (A) a chamber containing liquid of relatively high pressure,
  - (B) a chamber containing liquid of relatively low pressure,
  - (C) an accumulator chamber adapted to be periodically hydraulically connected to said chamber containing liquid of relatively high pressure and to said chamber containing liquid of relatively low pressure,
  - (D) an accumulator piston slidably disposed in said accumulator chamber and adapted to assume a position of rest, said accumulator piston displaceable from its position of rest by said liquid of relatively high pressure,
  - (E) means urging said accumulator piston against the force of said liquid of relatively high pressure and exerting to said accumulator piston a force increasing as a function of the displacement of said accumulator piston caused by said liquid of relatively high pressure,
  - (F) regulating means adapted to be periodically hydraulically connected to said accumulator chamber,
  - (G) a plurality of hydraulic conduits connecting said accumulator chamber with said chamber containing liquid of relatively high pressure with said chamber containing liquid of relatively low pressure, and with said regulating means,
  - (H) a throttle passage in at least said hydraulic conduit connecting said accumulator chamber with said chamber containing liquid of relatively low pressure, said throttle passage adapted to dampen the motion of said accumulator piston, and
  - (I) a control element for causing an opening and closing of said hydraulic conduits in a coordinated manner, said control element adapted, in sequence, to establish a first communication between said accumulator chamber and said chamber containing liquid of relatively high pressure, to establish a second communication between said accumulator chamber and said regulating means after breaking off said first communication and to establish a third communication between said accumulator chamber and said chamber containing liquid of relatively low pressure in a time period after breaking off said first communication and before establishing said second communication, said control element adapted to maintain said third communication for a duration being the function of the r.p.m. of said engine.
2. A hydraulic regulator as defined in claim 1, wherein said control element linearly reciprocates to perform alternating pressure strokes and suction strokes and is driven with a frequency depending upon the r.p.m. of said engine.
3. A hydraulic regulator as defined in claim 2 including a housing having a bore, said control element is formed as a piston and is slidably received in said bore, during said pressure strokes said bore constitutes said chamber containing liquid of relatively high pressure and during said suction strokes said bore constitutes said chamber containing liquid of relatively low pressure.
4. A hydraulic regulator as defined in claim 1 including an abutment disposed in said accumulator chamber and constituting said position of rest for said accumulator piston and adapted to be engaged thereby, said regulating means includes
  - (A) a cylinder,
  - (B) a regulating piston slidably disposed in said cylinder.

- der and adapted to assume a position of rest, said regulating piston displaceable from its position of rest by the pressure of liquid introduced into said cylinder,
- (C) spring means urging said regulating piston into its position of rest, and
- (D) an abutment constituting said last named position of rest and adapted to be engaged by said regulating piston, said spring means and said means urging said accumulator piston against the force of said liquid of relatively high pressure are dimensioned such that the hydraulic pressure necessary to displace said accumulator piston from its position of rest is at least as large as the hydraulic pressure necessary to displace said regulating piston from its position of rest.
5. A hydraulic regulator as defined in claim 4, wherein at least one of said abutments is adjustable.
6. A hydraulic regulator as defined in claim 1 including a transfer port leading from said accumulator chamber, said transfer port adapted to be opened by said accumulator piston when displaced to a maximum extent by said liquid of relatively high pressure, said relatively high pressure which is present in said accumulator chamber when said accumulator piston is displaced to said maximum extent is at least as large as the pressure necessary to displace said regulating means to a maximum extent.
7. A hydraulic regulator as defined in claim 6 including a throttle passage leading from said accumulator chamber

10

15

20

25

30

ber, said last named throttle passage is adapted to be opened by said accumulator piston before the latter opens said transfer port.

8. A hydraulic regulator as defined in claim 1, wherein in said hydraulic conduit connecting said accumulator chamber with said regulating means includes a throttle passage.

9. A hydraulic regulator as defined in claim 3 including a drain conduit leading from said bore, said control element adapted to maintain said drain conduit open upon completion of a pressure stroke and until starting a subsequent suction stroke.
